US00D751069S

(12) **United States Design Patent**
Choi et al.

(10) **Patent No.:** **US D751,069 S**
(45) **Date of Patent:** ** *Mar. 8, 2016

(54) **ELECTRONIC DEVICE**

(71) Applicant: **Samsung Electronics Co., Ltd.**,
Suwon-Si, Gyeonggi-Do (KR)

(72) Inventors: **Jaewoong Choi**, Seoul (KR); **Jeff Jones**,
San Francisco, CA (US); **Yongseok Bang**, Yongin-si (KR); **Howard Nuk**,
San Francisco, CA (US); **Wonseok Choi**, Seoul (KR); **Alex Millie**, San
Francisco, CA (US); **Jihyun Ko**, Seoul (KR); **Seung-Min Park**, Seoul (KR);
Hayoul Jung, Seoul (KR)

(73) Assignee: **Samsung Electronics Co., Ltd.**,
Gyeonggi-do (KR)

(*) Notice: This patent is subject to a terminal disclaimer.

(**) Term: **14 Years**

(21) Appl. No.: **29/499,944**

(22) Filed: **Aug. 20, 2014**

(30) **Foreign Application Priority Data**

Feb. 22, 2014 (KR) 30-2014-0009039

(57) **CLAIM**

The ornamental design for electronic device, as shown and
described.

DESCRIPTION

FIG. 1 is the front perspective view of electronic device
showing our new design;

FIG. 2 is the front view thereof;

FIG. 3 is the rear view thereof;

FIG. 4 is the left-side view thereof;

FIG. 5 is the right-side view thereof;

FIG. 6 is the top-side plan view thereof; and,

FIG. 7 is the bottom-side plan view thereof.

The broken lines in the drawings depict parts of the electronic
device that form no part of the claimed design.

1 Claim, 7 Drawing Sheets
